G. STIEGLER

WATCH CHAIN FASTENER

Filed Sept. 22, 1923.

INVENTOR:

George Stiegler

BY *Albert H. Lauer*

ATTORNEYS.

UNITED STATES PATENT OFFICE.

GEORGE STIEGLER, OF CINCINNATI, OHIO.

WATCH-CHAIN FASTENER.

Application filed September 22, 1923. Serial No. 664,322.

To all whom it may concern:

Be it known that I, GEORGE STIEGLER, a citizen of the United States, and a resident of Cincinnati, in the county of Hamilton 5 and State of Ohio, have invented certain new and useful Improvements in Watch-Chain Fasteners, of which the following is a full, clear, and exact description, reference being had to the accompanying drawing, forming part of this specification.

My invention relates to devices employed for securing watch chains to the wearer, in such a way that they cannot be removed.

In my United States Patent No. 1,457,716, 15 dated June 5, 1923, I have shown and described a device whereby the cross bar of a watch chain is held between two transverse arms against a suitable plate, over which the arms are elevated. In this patent I also show and describe a method of securing such a device to the waist band of trousers, and to garment supporting belts and the like.

It is my object in the present invention 25 to provide for a slider to be used on garment supporting belts, in which the structure of my former application is simplified without essential sacrifice of functions, rendering the device a better manufacturing proposition and also making its appearance neater and use more convenient.

I accomplish these objects by that certain construction and arrangement of parts to be hereinafter more specifically pointed 35 out and claimed.

In the drawings:

Figure 1 is a perspective view of one form of the device showing the front thereof.

Figure 2 is a like view of the device of Figure 1 showing the rear view.

Figure 3 is a plan view of the preferred and simpler form of the device.

Figure 4 is a side elevation of the device 45 of Figure 3.

Figure 5 is a rear elevation of the device of Figure 3.

Figure 6 is a perspective view showing the preferred form of device used with a 50 watch chain cross bar.

Figure 7 is a like view showing the method of holding in a watch chain on which no terminal button or bar is used.

Figure 8 is a like view showing the device used with a watch chain having a ter-

minal button, such as is usually designed for lapel use.

The essential feature of my invention relates to the provision of a means for holding fast the watch chain for men's wear, 60 when the watch is located in the trousers pocket, and the wearer is using a belt, and no vest.

It has been a problem to protect the watch in the summer time against falling out, and 65 being purposely removed by thieves and pickpockets, and my invention is believed to solve this problem in a very convenient and inexpensive manner.

In my present device the whole member is 70 formed as a slider for garment supporting belts, and is intended to be removed from the belt when the watch is removed, as upon changing trousers, retiring for the night, etc.

The device is thus formed with a back 75 1, which may be of any desired shape, the oval ring shaped structure being convenient of manufacture and having neatness of appearance. From the back there are two looped arms 2, 2, which form the ends 80 of the slider. I have shown two forms of front piece, one of which is intended for use with a chain cross bar only, and supports this bar against the front of the slider by means of the elevated arms. In this 85 form which most closely resembles my former invention, there are two elevated spaced arms 3, 3, and a front plate 4, which plate is of oval ring shape. The cross bar of a watch chain is in this device thrust in between the two arms, and can be manipulated because the oval ring shaped structure permits of its being twisted around behind the arms. The bar is thus twisted 90 about behind the arms, and thrust into a position so that the two ends of the cross bar lie over the ring shaped portion 4, and the chain extends out between the two arms. The slider when so equipped is set over the end of a garment supporting belt, and slid 95 along until it is in the desired position. The belt itself in this construction does not act as a limiting means or backing means, that contributes to the engagement of the cross bar.

I find, however, that where used as a slider the front plate or ring portion 4 can be done away with. Thus in the preferred form the slider back and the two looped arms may be the same, but the looped arms 100 105 110

themselves are connected by the two arched arms 3, 3. As so constructed the garment belt acts as the backing means which holds the watch chain bar, chain button or the 5 chain of itself in a position against becoming dislodged.

Referring to Figure 6, I show a watch chain 10, having a cross bar 11. In use the 10 slider is removed from the belt, and the watch chain bar thrust through the space between the two arms, being freed for movement by the ring shape of the back of the slider. The wearer then twists the bar about to a position (shown) where the 15 center of the bar is beneath the shape between the two arms. The slider is then placed over the belt and moved to desired position.

When in this position the chain bar cannot 20 be dislodged without taking off the slider, as it is necessary to tip the bar to get its end to pass through the space between the two arms. The belt prevents this tipping.

25 In Figure 8 I show the chain 10 as having a button 12 thereon. The usual button will be slightly larger across than the arched portion of the arms. The wearer removes the slider from his belt, and passes the watch 30 chain in through the back of the device, and out between the two arms, leaving the button in the space between the back of the slider and the arms. The slider may then be placed on the belt as before and the 35 button cannot be drawn out between the two arms. The size of the button is not a regular thing, but it may be observed that the belt serving as a backing for the button will not be unduly crowded by a button, 40 or a cross bar, due to the proper arrangement of the front of the slider. In the front plate form of Figures 1 and 2 should the button be too large to lie flush with the back of the front plate of the slider, then 45 the structure that was a good, snug fit when used with a cross bar would be too tight when used with a button.

50 Where the user has neither a button nor a cross bar, but has a watch at one end of his chain and some sort of a charm at the other, then the device in the preferred form which is a good fit when used with

cross bar and button will still be effective in retaining the chain. In this form (Figure 7) the chain is detached from the charms 55 or the watch as the case may be, and is passed through the slider beneath the two cross arms. The watch or charms are then fastened on again, and disposed of in the pockets of the trousers as desired. The 60 thickness of the charms will prevent the chain from being pulled out from the slider when same is on the belt, even though the charms be small enough to pass through the slider when separated. The usual chain will be held snugly enough against the belt in a properly fitting slider, so that it will not slide one way or the other therein when in use. Even were the charms removed from the chain, and the mere swivel 14 used, 65 still this swivel would be too large to pull lengthwise through the slider when on the belt. This is illustrated in Figure 7.

Having thus described my invention, what I claim as new and desire to secure by Letters Patent, is:—

1. A slider for garment supporting belts having on its front face a pair of elevated, spaced arms formed integrally with the back and so elevated that when the slider 80 is on a belt, a portion of the usual watch retaining member will lie beneath the arms, and against the belt, said slider being formed with a back which is open at the middle whereby a watch bar, button or the like can 85 be thrust through between the arms, without interference by the back.

2. In a device of the character described having a back, ends and a front disposed integrally theron and formed so as to slide 90 over a belt, the front comprising a pair of spaced arms, said arms being so elevated from the belt, and the front so formed that a portion of a watch supporting member can 95 lie against the belt beneath the arms, and the chain portion of such member can pass out between the two arms, the back of said member being provided with an aperture of sufficient size to permit the insertion through the arms from the front of a watch 100 chain cross bar, without interference by the back.

GEORGE STIEGLER.
